CLAIM

The ornamental design for a river tube with canopy, as shown and described.

DESCRIPTION

FIG. 1 is a bottom elevational view of the river tube with canopy showing my new design;

FIG. 2 is a perspective view thereof;

FIG. 3 is a front view thereof;

FIG. 4 is a rear view thereof;

FIG. 5 is a left side plane view thereof;

FIG. 6 is a right side plane view thereof;

FIG. 7 is a top plan view thereof;

FIG. 8 is a bottom plan view thereof;

FIG. 9 is an enlarged cross sectional view of the encircled portion of FIG. 1;

FIG. 10 is an enlarged cross sectional view of the encircled portion of FIG. 1;

FIG. 11 is an enlarged cross sectional view of the encircled portion of FIG. 2; and,

FIG. 12 is an enlarged cross sectional view of the encircled portion of FIG. 2.

The broken line showing of the eyelets is for the purpose of illustrating portions of the article that forms no part of the claimed design. The dot-dash lines that demarcate claimed areas in FIGS. 1 & 2 have been included to show enlargement for clarity. The lines themselves do not form part of the claimed design.
